BROAD-TAPE ILLUMINATOR

August D. Eitzen, Rockville Centre, N. Y., assignor to News Projection Corporation, New York, N. Y., a corporation of New York

Application May 1, 1937, Serial No. 140,197
Renewed December 1, 1938

6 Claims. (Cl. 40—82)

This invention relates to broad tape illuminators in general.

Among the objects of the present invention, it is aimed to provide an improved broad tape illuminator whereby the tape is advanced across the light aperture of a casing as the same is supplied by a ticker or the like and the tape wound up in back of the casing by a surface feed device to maintain the advancing movement substantially constant as the rewind reel increases in diameter.

It is still another object of the present invention to provide an improved broad tape illuminator whereby a tape is advanced across the light aperture of a casing and then over the top of the casing into surface feed engagement with a tape pulling or tape advancing device.

These and other features, capabilities and advantages of the invention will appear from the subjoined detail description of specific embodiments thereof illustrated in the accompanying drawings in which

Figure 1 is a perspective of a broad tape illuminator associated with a cabinet containing a broad tape printer;

Fig. 2 is an enlarged front elevation of the illuminator with the printer cabinet removed;

Fig. 3 is a section on the line 3—3 of Fig. 2;

Fig. 4 is a section on the line 4—4 of Fig. 3; and

Fig. 5 is an end elevation of another form of illuminator in which there is used an endless tape having characters or printed matter thereon.

In the embodiment shown, in Figs 1 to 4, there is provided a cabinet 1 for housing a broad tape ticker such as a Dow Jones ticker or the like from which the tape is fed upwardly through the slot 2 to the illuminator 3 constituting the main part of the present invention.

The illuminator 3 consists essentially of a rectangular casing 4 having a base 5, a front wall 6 with an opening or window therein preferably provided with a frame 7 for the light transmitting sheet 8 composed of glass or the like. The casing 4 also preferably has a top wall 9, side walls 10 and 11 and a rear wall 12 consisting of a sheet of metal which extends down as at 13 to be secured to the rear wall 14 of the cabinet 1. The side walls 10 and 11 preferably have openings 15 at the top and openings 16 at the bottom equipped with suitable louvers to provide for the entrance and exit of air in the interest of ventilation but at the same time obstructing the passage of light rays from the casing 4.

These side walls 10 and 11 furthermore extend above the wall 9 and are perforated to provide

supports for the idlers 17 and 18 extending the full length of the casing 4 and formed at the front and rear ends of the casing 4 to form guides for the tape 19 as it crosses the top of the casing 4.

After the tape leaves the ticker, not shown, which is intended to be housed in the cabinet 1 and passes through the opening 2, it passes under the idler 20 rotatably mounted in the arms 21 and 22 secured to the side walls 10 and 11 of the casing 4 and projecting forwardly of the wall 6 below the glass plate 8. The tape 19 then passes across the glass plate 8 or rather across the window provided with the glass plate 8, in the present instance, and then over the idlers 18 and 17 down to and onto the reel 23. The reel 23 is preferably weighted so that it may properly engage the drive roller 24 to effect surface feed of the reel 23.

The reel 23 is mounted on the shaft 25 which is slidably mounted in the guideways formed by the pairs of vertically extending strips 26 and 27 secured to the rearwardly extending wings 28 and 29 formed on the rear wall 12.

The drive roller 24 in the present instance is provided with a stub shaft 30 journalled in an orifice formed in the wing 29 while the roller 24 itself extends through the other wing 28 and is provided with another stub shaft 31 which is drivingly connected to the electric motor 32 connected to the outer side of the wing 28 by the bracket 33.

The casing 4 is preferably provided with any suitable source of light in the present instance, the upper wall 9 being provided with three downwardly extending sockets 34, 35 and 36 to receive the elongated tubular lamps 37, 38 and 39 respectively extending at least the full length of the window provided with the glass plate 8, see Fig. 4, and substantially the full width of this window, see Fig. 2.

In the embodiment shown in Fig. 5, it is shown how an endless tape 40 may be used with this same equipment. Here the endless tape 40 passes into the cabinet 41 through the opening 42 at the bottom thereof and then out again through the opening 43 at the top thereof from which it passes up under the idler mounted in the brackets 44 disposed at the bottom of the casing 45 and then up across the front of the window formed in the front of the casing 45 and then over the top and to the back of the casing 45 under the weighted roller 46 by which it is pressed into surface driving engagement with the drive roller 47 drivingly connected to the motor 48 from which it returns to the cabinet 41 through the opening 43.

It is obvious that various changes and modifications may be made to the details of construction without departing from the general spirit of the invention as set forth in the appended 5 claims.

I claim:

1. The combination of an illuminator for a broad tape including a casing having a window in a vertically extending wall, a source of light within said casing behind said window, guides for guiding the tape upwardly across said window and then over the top of said casing, a weighted 10 rewind reel for receiving the tape, vertically extending guideways for said reel behind said casing and at the lower end thereof, and a surface driving roller below said reel and in driving engagement with the tape on said reel, said guideways being open at the top to facilitate removal of said reel to wind up the tape on said reel.
2. The combination of an illuminator for a broad tape including a casing having a window in a vertically extending wall, a source of light within said casing behind said window, tape advancing means mounted behind said casing and 15 clear of said source of light, and guides at the bottom of said window and on the top of said casing to guide the tape across said window and then over said casing to said advancing means.
3. The combination of an illuminator for a broad tape including a casing having a window in a vertically extending front wall, a top wall, lamps extending down from said top wall behind 20 said window, tape advancing means mounted behind said casing and below the level of said lamps, and guides at the bottom of said window and on the top of said casing to guide the tape across said window and then over said casing to said advancing means.
4. The combination of an illuminator for a broad tape including a casing having a window 25

in a vertically extending front wall, a top wall, lamps extending down from said top wall behind said window, a rear wall having a downward extension and rearwardly extending wings, the downward extension serving as a support for 5 connecting the casing to a ticker cabinet, advancing means supported by said wings and clear of said lamps, and guides connected to said casing for guiding the tape across said window and then over said casing to said advancing means.

5. The combination of a ticker cabinet having a tape discharge opening in the top wall thereof, a casing connected to said cabinet and having a window in a vertically extending wall in substantial alignment with said opening, a source of 10 light within said casing and behind said window, a rear wall having a downward extension and rearwardly extending wings, the downward extension serving as a support for connecting the casing to said ticker cabinet, tape advancing 15 means supported by said wings and clear of said lamps, and guides for guiding the tape upwardly from said opening across said window and then over said casing to said advancing means.

6. The combination of an illuminator for a broad tape including a casing having a vertically extending front partition having a window therein, a source of light behind said window within 20 said casing, a weighted roll, wings extending rearwardly from said casing, a continuously driven 25 drive roll operatively mounted on said wings and below said weighted roll, vertically extending guideways on the inner opposing faces of said wings for receiving said weighted roll and enabling it to press the tape into surface feeding 30 engagement with said drive roll, said guideways being open at the top to facilitate removal of said roll.

AUGUST D. EITZEN. 40
